UNITED STATES PATENT OFFICE.

ELLING ELLINGSON, OF CANTON, SOUTH DAKOTA, ASSIGNOR TO BRAGSTAD CONCRETE MACHINERY CO., INC., OF CANTON, SOUTH DAKOTA, A CORPORATION OF SOUTH DAKOTA.

CONCRETE-BLOCK-MOLDING MACHINE.

1,118,540.

Specification of Letters Patent. Patented Nov. 24, 1914.

Application filed February 17, 1913. Serial No. 748,911.

To all whom it may concern:

Be it known that I, ELLING ELLINGSON, a citizen of the United States, and residing at Canton, in the county of Lincoln and State 5 of South Dakota, have invented certain new and useful Improvements in Concrete-Block-Molding Machines, of which the following is a specification.

This invention relates to concrete block 10 molding machines, and relates more specifically to a machine of this type adapted particularly for the molding or forming of what is generally termed a "sectional block," that is, a molded concrete block 15 which is formed of sections fixedly secured together, but so disposed with relation to each other as to provide a continuous air space interiorly of the completed block.

The present invention is an improvement 20 upon the device shown, described and claimed in Letters Patent #951,728, granted to Joseph W. Bragstad on March 8, 1910, and the present invention has for its object to improve the operating means for manipulating the end cores of the mold, in such manner as to render the device more positive in its action, and prevent any movement 25 of the end sections of the core during the process of molding the block.

30 In the drawings: Figure 1 is a view in side elevation of a concrete block molding machine in accordance with my invention, the mold being shown in closed position. Fig. 2 is a similar view of the machine, the mold being shown in the opened position. Fig. 3 is a top plan view of the machine 35 with the mold in the closed position. Fig. 4 is an end view of the machine with the supporting legs partly broken away. Fig. 5 is a longitudinal sectional view of the machine with the mold in the closed position, and, Fig. 6 is a detail perspective view of 40 one of the end boards of the mold with its attached operating mechanism and also 45 showing more in detail the wear take-up mechanism.

The present invention, like the device shown in Patent #951,728 above referred to, employs a mold embodying side and end 50 members, the side members being hinged to move from upright to substantially horizontal positions, and the end members which

carry a part of the core for the complete block, being adapted to move endwise of the machine toward and away from the center 55 thereof. Certain details of construction in the machine shown in said Letters Patent #951,728, and in my improvement being therefore in common, detailed description of such parts is deemed unnecessary, such detailed description as is given herein being directed substantially to the improvements.

As in the patent above referred to, I provide a suitable supporting bed or base 10, having suitable supporting legs 11, and 65 which supporting base or bed is generally formed of side and end rails as shown.

In order to produce a sectional concrete block such as is fully shown in Fig. 8 of Patent #951,728 above referred to, side and 70 end members are employed, the end members carrying portions of the core, which portions of the core coöperate with a vertically-movable core section to form the completed block.

75 In the present invention, like in the device shown in the patent above referred to, the end members of the mold carry core sections which coöperate with a vertically-movable core section. As the manner in 80 which the anchors that secure the sections of the completed block fixedly together are placed in position in the mold is fully shown and described in the patent above referred to, it is not believed necessary to illustrate 85 or describe in detail such feature in the present invention.

Like in the patent above referred to, I provide for the mold, a pallet plate 12, which it will be understood is suitably apertured to accommodate the vertically movable core sections used in producing the block. This pallet plate rests upon the bed or base 10 and coöperates with the side members 14 and the end members 15 to form the 95 mold. The side members 14 in accordance with my invention are hinged at the opposite sides of the bed or base plate to pintle rods 16, which pass through the lower ends of the ribs 17 on said side members and 100 have their ends received in bosses 18 carried by the sleeves 19 that are adjustably mounted on stub shafts 20 carried by the side rails of the base or frame. These sleeves 19 may

be adjusted on the stub shafts 20 to increase or decrease the space between the side members 14, being held in an adjusted position in any suitable manner as by set screws passing through the sleeves and impinging against the stub shafts 20.

The end members in addition to carrying core sections 21, similar to the core sections shown in Patent #951,723, carry on their inner faces adjustable clips 22, which are positioned so as to close against the outer faces of the side members 14 at the ends thereof, and thus hold the side sections in upright position when the end sections are moved up to closed position. In practice, the adjustability of the clips or brackets 22 is easily effected by making these in the form of an angle iron, one leg of which lies against the inner faces of the end sections, and the other leg of which engages the outer faces of the side sections, the end sections being provided with a plurality of apertures 23 through one or the other of which securing bolts are passed for fastening the clips to the end sections.

In Patent #951,723 heretofore referred to, a cable mechanism is employed for opening and closing the end members of the mold, and in practice, it has been found that these cables stretch or give, resulting at times in an imperfect block, the mold members, and particularly the end members of the mold being unable to resist the strains imposed thereon resulting in an untrue or imperfect block. To obviate this, is as heretofore stated, one of the main objects of my invention, and I accomplish this by means which will now be described specifically to the embodiment shown.

Each end member 15 is provided on its outer face with bearings 24 in which is mounted a rock-shaft 25; the ends of which extend beyond the respective bearings 24, and are connected with the respective ends of the base or bed, by a toggle lock, which when in closed position, serves effectively to resist any movement of the end members of the mold. One of these toggle locks is provided for each end member 15, and each lock consists of a somewhat triangular bracket 26, the two arms of which are connected at their free ends to the rock shaft 25, and at their outer or united ends, have a downwardly-projecting lug 27 which is pivotally connected by a wear take-up device with a bracket 28 mounted on the end of the base or bed 10. Said wear take-up device as here shown consists of a socket 29 pivotally-connected at its inner end to the lug 27 and having a threaded bore in its other end which receives one end of a right and left hand threaded screw 30, the other end of said screw 30 being received in the threaded bore of a socket 31 which has its outer end pivotally connected to the

bracket 28. The screw 30 is operated in any suitable manner, as by forming the central portion thereof with flattened faces to receive a spanner wrench, or by providing apertures in the screw to receive an implement, as is well-known in the arts. The socket member 31 is provided on its upper face with a seat 32 which receives an angularly-extending pin or projection 33 carried at the free end of a locking lever 34, which at its inner end is fixedly attached to the bracket 26. The locking lever 34 constitutes a handle for breaking the toggle joint to permit of the end members of the mold being moved outwardly, and when the pin 33 is engaged in the seat 32, said lever 34 holds the toggle lock in locked position.

As in Patent #951,723, I employ a central core section 35 carried by a rack 36 held against lateral movement during its operation by a brace guide 37. Said central core section is operated by means of a toothed segment 38 engaging the rack 36, as in Patent #951,723 referred to, said segment being mounted on a shaft 39 carried in hangers 40 attached to the opposite side rails of the bed or base. The shaft 39 is operated to move the segment by an operating lever 41 mounted on one end of said shaft 39. At each end of the machine frame, I provide, on each side thereof, and underneath the bed or base, supporting brackets 42 of somewhat angular shape, one end of each bracket being attached to the side rails of the bed or base, and the other end of each bracket being attached to the supporting legs 11. These brackets constitute bearings for cross-shafts 43, 43' at one end of the machine and similar shafts 44, 44' at the other end of the machine. Said cross-shafts extend beyond the brackets or bearings 42 at opposite sides of the machine, and at one end of the machine, on both sides thereof, there is attached to the respective ends of the shaft 43 the lower ends of levers 45, the upper ends of which are pivotally attached to the outer ends of links 46, having their inner ends pivotally attached to the rock shaft 25 at the end of the machine. At the same end of the machine, on both sides thereof, there is attached to the ends of cross-shaft 43', the lower ends of levers 47, having their upper ends mounted on the ends of rock shaft 25. At the other end of the machine, at each side thereof, there is provided a relatively long and a relatively short lever designated 48 and 49 respectively.

The short levers 49 are similar to the levers 45 at the opposite end of the machine, and their lower ends are mounted on the projecting ends of cross shaft 44', while their upper ends are connected to the outer ends of links 46 in the same manner as heretofore described for the levers 45 at the op-

posite end of the machine. The levers 48 are, however, mounted intermediate their ends on the ends of cross-shaft 44, so as to provide arms 48' depending below the cross-shaft 44. 5 The lower ends of these arms 48' are pivoted as at 50 to the lower ends of links 51 which have their other ends pivotally attached to the upper ends of links 52, (Fig. 5,) which are mounted on the shaft 39. Pivotally connected to these links 52 are the inner or lower ends of levers 53, the outer or upper ends of which are pivotally connected as at 54 to the levers 47, intermediate the ends of the latter. The upper portions of the levers 15 48 are mounted on the ends of the rock shaft 25 carried by the end member 15 at one end of the machine in the same manner as the upper ends of levers 47 are mounted on the rock shaft 25 carried by the end member 15 20 at the opposite end of said machine.

In Fig. 1 the tamper 55 is illustrated in position over the mold for tamping the material therein, but as the tamping mechanism *per se* is a separate invention from that herein shown and described, it has not been illustrated in detail. In said Fig. 1, the machine is shown with the mold closed, ready to receive the material from which the block is to be molded. When the block has been 30 molded and set, and it is desired to remove the same, the operator throws lever 41 to the left as illustrated in Fig. 2, which operates shaft 39, causing segment 38 to move rack 36 downwardly carrying the central core 35 therewith. Through the connection of the links 51, 52 and levers 53, with the levers 47 and 48, at apposite ends of the machine, the toggle lock, when locking levers 34 are released, will assume the position shown in 35 Fig. 2 of the drawings, moving the end members of the mold toward opposite ends of the bed or base, and allowing the side members 14 to open outwardly, so that the block may be removed from the bed or base. In 40 case it is desired to increase the size of the mold, a larger sized pallet plate is substituted, the side members 14 are adjusted outwardly on the stub shafts 20, the holding clips 22 are adjusted to conform to the increased width 45 between the side members, and a block of greater size thereby formed without other alteration or adjustment of the machine. The toggle lock mechanism holding the end

members of the mold secure in their position, obviates any necessity for providing 55 any locking means for the operating lever 41, necessitating only the operation of the locking levers 34, when it is desired to operate the lever 41 to open the mold.

Having thus described my invention, 60 what I claim as new and desire to secure by Letters Patent is:—

1. In a concrete-block forming machine, the combination with a mold comprising side and end members, of positively-operating means for moving said end members toward or away from the side members to open or close the mold, and means for connecting said end members with their support and holding said members in closed engagement with the ends of the side members, comprising an angular bracket having a depending lug, and a take-up device consisting of two members having oppositely-threaded bores, one of said members being 75 pivotally-secured to said support, and the other to the machine frame and a right and left screw connecting said threaded members, and a lever secured at one end to said bracket and provided at its free end with a 80 projection to engage one of the threaded members of the take-up.

2. In a concrete-block forming machine, the combination with a mold comprising side and end members, positively-operating 85 means for operating the end members toward or away from the side members to open or close the mold, and means connecting said end members with their support, and holding said members in closed engagement with the ends of the side members, comprising an angular bracket having a depending lug, and a take-up device having 90 one of its parts pivotally secured to said support, and its other member pivotally connected to the machine frame, a screw connecting said parts adjustably, and a lever secured at one end to said bracket, its opposite end having an angularly-projecting pin 95 to engage the adjacent take-up member. 100

In testimony whereof I affix my signature in presence of two witnesses.

ELLING ELLINGSON.
